CLAIM

The ornamental design for an electronic view finder, as shown and described.

DESCRIPTION

FIG. 1 is a front perspective view of an electronic view finder showing our new design;

FIG. 2 is a rear perspective view thereof;

FIG. 3 is a top view thereof;

FIG. 4 is a front view thereof;

FIG. 5 is a rear view thereof;

FIG. 6 is a right side view thereof;

FIG. 7 is a bottom view; and,

FIG. 8 is a left side view thereof.

The broken lines depict portions of the electronic view finder which form no part of the claimed design.

1 Claim, 8 Drawing Sheets
